UNITED STATES PATENT OFFICE.

ISAAC BARNETT, OF NEW YORK, N. Y.

BILL-FOLD.

972,494.

Specification of Letters Patent. Patented Oct. 11, 1910.

Application filed December 18, 1909. Serial No. 533,970.

To all whom it may concern:

Be it known that I, ISAAC BARNETT, a citizen of the United States, residing at New York, in the county of New York and State 5 of New York, have invented certain new and useful Improvements in Bill-Folds, of which the following is a specification, reference being had therein to the accompanying drawing.

10 My invention relates especially to devices for carrying bank bills, cards, commutation tickets, etc., in the pocket, and has for its object the provision of a simple, cheap, convenient, compact device of this character.

15 To attain the desired end, my invention consists in certain novel and useful combinations or arrangements of parts, and peculiarities of construction and operation, all of which will be hereinafter first fully described, and then pointed out in the claim.

In the drawing, Figure 1 is a plan view of a holder embodying my invention. Fig. 2 is a longitudinal, sectional view at line $a-a$ of Fig. 1, and Fig. 3 is a vertical, cross-sectional view at line $b-b$ of the same figure.

Similar numerals of reference, wherever they occur, indicate corresponding parts in all the figures.

1 is the back of the folder, made of leather, or any other preferred or appropriate material, such as leatherette, cloth, buckram, etc.

2 is the front portion of the body of the folder.

3 is a longitudinal division between the back and front portion of the device, which may be opened at the top, as illustrated in Fig. 3 of the drawing.

4 is a catch for holding the parts together above the partition 3.

Upon the front-piece 2 is secured a pocket 5, having a front of transparent celluloid,

said pocket being open at 6 for the insertion or removal of a ticket, such as a commutation ticket, the face of which may be examined without removal from the pocket, and by locating said pocket at the end of the folder, only the fold containing such pockets will be displayed. The center of the front of the folder is provided with a pocket 8, 50 secured only at the top and bottom, so the space back of it may be utilized, and such pocket 8 has a receptacle 9 for holding a removable book, such as 10.

11 is a pocket for cards, open only at 12. 55

It will thus be seen that I have provided a simple, cheap, and effective bill folder, having a plurality of compartments for the reception of bills; means being provided for retaining said bills within the compartment; 60 a ticket pocket, card pocket and a memorandum book holder, all assembled in a compact manner.

Having now fully described my invention, what I claim as new therein, and desire to 65 secure by Letters Patent, is:

As an article of manufacture, a bill fold in which is comprised a body having a compartment extending the entire length thereof, a longitudinal division therein of less 70 height than the side walls of the compartment, a catch located above said division and adapted to secure the side walls together, and a plurality of transverse compartments carried at one side of the longitudinal body of the bill fold, substantially 75 as shown and described.

In testimony whereof I hereto affix my signature in presence of two witnesses.

ISAAC BARNETT.
